UNITED STATES PATENT OFFICE.

JOHN L. CATCHPOLE, OF FRAMSDEN, AND GEORGE F. STIDOLPH AND THOMAS F. STIDOLPH, OF WOODBRIDGE, GREAT BRITAIN.

IMPROVEMENT IN SEED-SEPARATORS.

Specification forming part of Letters Patent No. 171,502, dated December 28, 1875; application filed September 28, 1875.

To all whom it may concern:

Be it known that we, JOHN LAST CATCHPOLE, of Framsden, and GEORGE FREDERICK STIDOLPH and THOMAS FREDERICK STIDOLPH both of Woodbridge, all in the county of Suffolk, England, subjects of the Queen of Great Britain, have invented or discovered new and useful improvements in apparatus for separating bodies of different shapes and sizes, more especially applicable for cleaning seed; and we, the said JOHN LAST CATCHPOLE, GEORGE FREDERICK STIDOLPH, and THOMAS FREDERICK STIDOLPH, do hereby declare the nature of the said invention, and in what manner the same is to be performed, to be particularly described and ascertained in and by the following statement thereof—that is to say:

This invention has for its object improvements in apparatus for separating bodies of different shapes and sizes, more especially applicable for cleaning seed.

The apparatus consists of a case having an inclined bottom, in which case are fixed inclined shelves. The shelves are arranged one above another in such manner that the bottom of each is not vertically over the top of the next, but leaves a small space between.

When cleaning seed the seed is fed into the case by a hopper, and falls onto the top shelf, along which it travels, and then falls onto the second shelf, and from thence to the third, and so on. The good seed, being rounded and heavier than the dross, travels with a greater velocity, and is able to jump over the space between the shelves, while the dross, traveling slower, drops down between the shelves, and falls onto the bottom of the case, from whence it is removed. The good seed is collected from the bottom shelf.

If required, the shelves may be covered with cloth or other suitable material, so as to give more friction, and thus retard the rough impurities.

The apparatus is especially adapted for cleaning clover-seed, which is a round seed, and, as collected, is commonly mixed with plantain-seed, which is longer and lighter than the clover-seed. Other seeds, coals, and almost every sort of body, can be cleaned in this machine.

In order that our invention may be most fully understood and readily carried into effect, we will describe the drawing hereunto annexed.

The figure shows a vertical section of the apparatus.

a is the case, with an inclined bottom. *b* are the inclined shelves. These shelves are, by preference, fixed to two side boards, *c*, thereby forming a sort of ladder, which is hinged to the case at *d*, so that by raising or lowering the lower end of the ladder the inclination of the shelves can be altered to suit different sorts of seeds and other bodies. *e* is a stop, pivoted at one end, and there locked by a nut, and which serves to support the ladder at any desired elevation. The ladder can readily be removed by taking out the pin on which it is hinged, and another ladder can be substituted, so that various sets of shelves, each suited to one particular sort of seed or other body, may be used in one outer case. For example, for clover-seed we prefer to have the shelves covered with cloth, whereas for grass-seed we use plain board. In some cases, for very dirty seed, we make the shelves, or some of them, of wire-gauze. *f* is the hopper, and *h* is an inclined shelf, onto which the seed drops from the hopper. This shelf is hinged at its upper end, so that its height and inclination may be varied to suit different sorts of seeds and other bodies by giving them different initial velocities. It is supported in position by a stop similar to the stop *e*, which supports the shelves. *g g* are two holes in the bottom of the case for the dross to run out of. The lower one is provided with a hinged stop, or otherwise, which projects slightly into the case, thus preventing the dross from mixing with the good seed which flows out at the end.

Having thus described the nature of our said invention, and the manner of performing the same, we would have it understood that what we claim is—

1. The combination, substantially as set forth, of the case, its inclined bottom, and the inclined shelves, arranged, as described, in a step-like series above the bottom of the case, and having vertical spaces between them, communicating with an inclined passage-way

formed beneath the shelves upon the bottom, for the purpose specified.

2. The combination, substantially as hereinbefore set forth, of the hopper, the case, its inclined bottom, the inclined shelves, and the hinged adjustable side boards, to which the shelves are fixed, for the purpose specified.

3. The combination, substantially as hereinbefore set forth, of the case, its inclined bottom, perforated toward its lower end, the inclined shelves, arranged above the bottom,

one below the other, with spaces between them, and the stop projecting from the bottom into the case, for the purpose specified.

JOHN LAST CATCHPOLE.

G. F. STIDOLPH.
